UNITED STATES PATENT OFFICE.

JOHN G. SULLIVAN, OF WINNIPEG, CANADA.

ANTICREEPER FOR RAILWAYS.

No. 808,952.

Specification of Letters Patent.

Patented Jan. 2, 1906.

Application filed July 8, 1905. Serial No. 268,826.

To all whom it may concern:

Be it known that I, JOHN G. SULLIVAN, a subject of the King of England, residing at Winnipeg, in the Province of Manitoba and Dominion of Canada, have invented a new and useful Improvement in Anticreepers for Railways, of which the following is a specification.

This invention relates to an improved anchoring device or anticreeper for preventing the longitudinal movement of track - rails, commonly termed "creeping."

Creeping results from expansion and contraction of the rails due to changes of temperature, such movement following the lines of least resistance, and it is also due to the action of trains. On steep grades and where the track is laid over bogs or muskegs or on similar soft ground such creeping becomes serious. Over bogs and muskegs it is well known that creeping takes place to a considerable extent, the rails moving as much as eight inches during the passage of a single train for a short distance, varying with the length of the bog, up to four or five miles. This tendency of the rails to creep is especially aggravated on double-track or four-track roads, where the traffic over each track is always in one direction.

It is the purpose of my invention to provide an inexpensive device which effectually resists such creeping and which can be readily applied to the track.

In the accompanying drawings, Figure 1 is a horizontal section of a portion of a track embodying the invention, the plane of the section being immediately below the rail-heads. Fig. 2 is a cross-section in line 2 2, Fig. 1, on an enlarged scale. Fig. 3 is a sectional top plan view, on an enlarged scale, of the construction shown in Fig. 1. Fig. 4 is a view similar to Fig. 1, showing a modification of the improvement. Fig. 5 is an enlarged cross-section in line 5 5, Fig. 4.

Similar letters of reference indicate corresponding parts throughout the several views.

A indicates the rails of one side of a track. They are spiked or otherwise fastened to the ties B, which may be of any suitable construction or material, the rails resting upon the customary metallic plates C.

D indicates the usual angle bars or plates which connect the adjoining rails.

Referring to the construction shown in Figs. 1, 2, and 3, E indicates an anticreeper-bar arranged lengthwise on one side of the

rail or rails and firmly secured to the ties or supports B by ordinary spikes f or other suitable fastenings. This bar rests upon the base of the rail and the ties and extends continuously over a plurality of ties, preferably from angle-bar to angle-bar, as shown in Fig. 1, although in some cases it may extend over but half that distance or even less, according to the character of the ground or road-bed. 60 When the anticreeper-bar extends throughout the distance from one angle-bar D to the next, it abuts at both ends against the opposing ends of the angle-bars, as shown in Fig. 1; but when the anticreeper-bar extends 65 over less than that distance it abuts against one of the angle-bars only. On single-track roads, where the traffic is in both directions, the bars E preferably abut against the angle-bars at both ends, while on double-track or 70 four-track roads, where the traffic on each track is in one direction, they abut only at their rear ends with reference to the direction of the traffic.

On steep grades and in bogs or muskegs, 80 where the track is especially liable to creep, it is desirable to apply the bars E to both sides of the rails, as shown in Figs. 4 and 5, and in localities of that character the bars may be extended along a greater or less number of 85 rails, as required.

The anticreeper-bars are preferably secured to the bases of the rails between the ties by a suitable number of bolts g, having lugs g', which engage under the base of the 90 rails, as shown in Fig. 2, or by other suitable fastenings. These bolts keep the bars E against the base of the rails, preventing the same from pulling up the spikes f and rattling.

It will be understood from the foregoing description that in each of the several embodiments of the invention above described one or more of said anticreeper-bars E are fastened to a number of the ties or rail-supports and abut at one or both ends against the angle-bars D or equivalent stop members secured to the rails. The longitudinal strains to which the rails are subjected by the traffic are therefore transmitted by the anticreeper-bars to the several ties to which they are fastened, thus distributing the strains over all of such ties and effectually resisting creeping of the rails. In other words, the use of such continuous anticreepers or anchor-bars renders it impossible for the rails to become displaced longitudinally without moving all of 95 100 105 110

the ties or supports to which said bars are fastened. These bars are simple in construction and their cost is comparatively small, and as they are continuous and coextensive with a plurality of ties they can be applied to the track more readily than a series of separate devices which must be individually applied to the rails and ties.

I claim as my invention—

- 10 1. The combination of the rails, the ties or supports thereof, a stop member secured to the rails, and a longitudinal anticreeper-bar secured to a plurality of said supports and abutting endwise against said stop member, whereby the longitudinal strains received by the rails are transmitted to and distributed over a number of the ties or supports by the anticreeper-bar, substantially as set forth.
- 15 2. The combination of a pair of adjoining rails, the ties or supports thereof, plates connecting the adjoining ends of the rails, and a longitudinal anticreeper-bar fastened to a plurality of the rail-supports and abutting at its end against said connecting-plate, substantially as set forth.
- 20 3. The combination of a series of rails, the ties or supports thereof, plates connecting the adjoining ends of the rails, and a longitudinal anticreeper-bar secured to a plurality of the ties or supports and abutting at their ends against said connecting-plate, substantially as set forth.
- 25 4. The combination of a pair of adjoining rails, the ties or supports thereof, plates connecting the adjoining ends of the rails, a longitudinal anticreeper-bar fastened to a plurality of the rail-supports and abutting at its end against said connecting-plate, and means for fastening the anticreeper-bar to the portions of the rails, between the ties, substantially as set forth.

the ties, said bar extending from the connecting-plate of one rail-joint to the connecting-plate of the next joint and abutting at its ends against said plates, substantially as set forth.

4. The combination of a pair of adjoining rails, the ties or supports thereof, plates connecting the adjoining ends of the rails, a longitudinal anticreeper-bar fastened to a plurality of the rail-supports and abutting at its end against said connecting-plate, and means for fastening the anticreeper-bar to the portions of the rails, between the ties, substantially as set forth.

5. The combination of a pair of adjoining rails, the ties or supports thereof, plates connecting the adjoining ends of the rails, and longitudinal anticreeper-bars arranged on opposite sides of the rails and secured to a plurality of the ties and abutting at their ends against said connecting-plates, substantially as set forth.

Witness my hand this 23d day of June, 1905.

JOHN G. SULLIVAN.
